UNITED STATES PATENT OFFICE.

RUSSELL H. BURR, OF WEST MERIDEN, CONNECTICUT, ASSIGNOR TO
C. ROGERS & BROS., OF SAME PLACE.

DESIGN FOR COFFIN-HANDLE SOCKETS.

Specification forming part of Design No. **8,039**, dated February 2, 1875; application filed January 22, 1875.
[Term of Patent 7 years.]

CASE C.

To all whom it may concern:

Be it known that I, RUSSELL H. BURR, of West Meriden, in the county of New Haven and State of Connecticut, have invented a new Design for Coffin-Handle Socket; and I do hereby declare the following, when taken in connection with the accompanying drawings, and the letters of reference marked thereon, to be a full, clear, and exact description of the same, and which said drawings constitute part of this specification, and represent a front view.

This invention relates to a design for the sockets by which the handles are attached to coffins; and consists in the peculiar configuration or outline of the socket, as shown in the accompanying illustration.

The upper, lower, and outer edges of the base are formed alike, the general outline being that

of a quarterfoil. At the intersection of the segments which make such quarterfoil a circular recess, *a*, is formed, and a recess, *d*, in the circumference of these segments, midway between the recesses *a*. The inner edge, *A*, is to a great extent hidden by the handle, and may be of any form, that being no part of this design. The ear *B* is centrally arranged upon the plate, in the usual manner, and may be of any form, the outline of the socket-base constituting the essential feature of this design.

I claim—

The design for coffin-handle socket, as herein described, and shown in the accompanying illustration.

RUSSELL H. BURR.
